IGNITING DEVICE FOR OIL BURNERS

Ivan V. Abadjieff, Auburn, Mass., assignor to Leland-Gifford Company, Worcester, Mass., a corporation of Massachusetts

Application August 13, 1932, Serial No. 628,708

3 Claims. (Cl. 158—10)

This invention relates to range-type oil burners and to igniting devices therefor.

A range-type oil burner usually comprises a base which carries a pair of spaced perforated combustion tubes or cylinders and has an open top fuel channel which underlies the combustion space between said tubes. At the time of starting the burner in operation, the channel contains liquid oil or other liquid combustible supplied through a control valve from a constant level oil chamber in which oil is maintained commonly from an inverted oil bottle. The oil in the channel is ignited, usually, by introducing a burning igniter downwardly in the combustion space between the combustion tubes and into contact with the oil in the channel. Sometimes the channel contains a wick to facilitate the ignition of the oil. In accordance with the present invention the igniting device may comprise a wire rod of sufficient length having a handle at one end and a porous mass of oil-saturated non-combustible material at the other end which is adapted to be ignited to ignite the oil in the burner. The porous material can contain a substantial amount of oil and the flame cannot be blown out readily after it has served its purpose. Hence an object of the present invention is the provision of an igniting device having a novel flame-snuffer incorporated therewith and so arranged that, when desired, the snuffer can fall into position to enclose the flaming material and extinguish the flame.

Heretofore, no convenient storage receptacle for the igniting device has been proposed and hence it is a further object of the invention to provide such a receptacle in the form of a hollow supporting standard for the oil bottle or reservoir and in which standard the igniting device is adapted to be stored, with the snuffing device having means for closing the opening in the standard and also for supporting the snuffing device in a position on the igniting device where it can more or less automatically be held away from the oil saturated material at the time the igniting device is in use.

A further object is generally to improve the construction of oil burners and igniting devices therefor.

Fig. 1 is a side elevation of an oil burner embodying the present invention.

Fig. 2 is an elevation of the igniting device.

Fig. 3 is a sectional elevation through the hollow supporting standard of the oil reservoir of the burner with the igniting device contained therein.

Fig. 4 is a sectional detail of a modified form of snuffing device.

Fig. 5 is a sectional detail of a further modified form of snuffing device.

The oil burner associated with the present invention includes a burner base 10 having an open top fuel channel 12 and supporting a pair of concentric spaced perforated combustion tubes 14 and 16 on opposite sides of and upstanding above the top of the channel. Sometimes a wick 18 is disposed within the channel 12. The burner is adapted to be contained within the fire box of a coal range, not herein shown. At the time of starting the burner, oil is admitted into the fuel channel through a pipe 20 and a control valve 22 from a constant-level oil chamber 24 to stand at some level in the channel corresponding to the level of oil in the chamber. The chamber receives the mouth of an inverted oil-containing bottle or reservoir 26 and thus maintains oil in the chamber. The chamber and bottle are supported on a vertical standard 28 which, in accordance with the present invention, is hollow and open at the top, and is composed of a section of pipe or tubing and is fixed to and supported at the bottom by feet 30.

The igniting device for the oil in the channel 12 comprises a straight and stiff small diameter metal rod 32 of sufficient length to extend from the top of the combustion tubes 14 and 16 through the space therebetween and into contact with the wick 18 or with the oil in the channel. The rod at its upper end is provided with a suitable handle herein shown as a loop 34 formed at the end of the rod. A mass of porous oil-absorbent material 36, preferably non-combustible, as asbestos fibres, is secured to the lower end of the rod and is adapted to absorb and retain a suitable amount of oil. The material can be charged with oil by immersing it in the oil in the chamber 24, after which the oil-saturated material can be ignited and inserted in the burner to ignite the oil therein. After the burner has been ignited the flame of the igniting device should be extinguished. It is difficult to blow out the flame by reason of the substantial amount of burning oil; and this manner of extinguishing the flame is objectionable because of the odor of the oil vapors. Hence the igniting device is provided with a snuffing device which extinguishes the flame practically instantly and encloses and cools and thus prevents the liberation of much objectionable odor.

The snuffing device 38 comprises essentially a plate 40 which has a passage 42 therethrough in which the rod 32 of the ig-

niting device is slidable and which is held from detachment from said rod by the loop 34 at the upper end and by the mass 36 of absorbent material at the lower end of the rod. A cylinder 5 44 is integral with said plate and depends therebelow and is concentric with the rod passage 42 and has a recess 46 therein which is closed by said plate 40 at the top and is open at the bottom. Said recess preferably is longer than said 10 mass 36 of absorbent material and has a lateral dimension sufficient to receive and confine said material closely. Thus, when the snuffer is permitted to drop on the rod 32 the absorbent material passes into said recess and the flame is 15 instantly extinguished, the oil also being cooled by the cool snuffer so that oil vapors are not liberated.

Also in accordance with the present invention the snuffing device is arranged to constitute a support for the igniting device when not in use 20 within the hollow standard 28. To this end, the plate 40 of the snuffing device is circular and is large enough in diameter to overlie the open end of and rest upon the end of the standard and has 25 a marginal depending rim or flange 48 within which the top of the standard is located and by which the plate is held against lateral displacement. The igniting device thus is supported 30 pendently within the standard by the snuffing device, the ring 34 engaging the top of the plate 40 and said plate constituting a closure for the open top of said standard so as to prevent the escape of any odors that may emanate from the saturated mass 36. The plate 40 also constitutes 35 a holder for the snuffing device at the time the igniting device is in use, the rim of the plate 40 and the handle 34 of the igniting device being grasped concurrently by the hand at the time the igniting device is being withdrawn from the 40 standard and lighted and inserted in the burner, so that the snuffing device is thus more or less automatically held at the top of the rod 32. After the burner has been lighted, the snuffing 45 device is released and falls over the flaming mass 36 and extinguishes the flame. The igniting device is then restored to its position within the standard.

It will be apparent that, by the present invention, I have provided a convenient igniter for 50 oil burners, that is always at hand when needed and wherein any fire hazard accompanying the use and storage of the device is eliminated.

Fig. 4 illustrates a modified form of snuffing device composed of stamped or pressed sheet metal parts, the plate 40a having a recess 50 in 55 which the upper end of a snuffing tube 44 is

pressed and a rod-guide 42a being secured in an aperture in said plate.

Fig. 5 illustrates a further modified form of the device wherein the snuffing tube 52 has a reduced neck 54 that slidably receives the rod of the 5 igniting device, the neck being fixed in a flanged opening of the plate 40b which, otherwise, has the same general construction and functions as the plate 40.

I claim:

1. An igniting device for oil burners comprising a long slender rod having a handle at the upper end and a porous mass at the lower end, and a snuffing device for the flame of said porous mass, said device being freely slidable on said rod 15 and retained against detachment therefrom at one end by said handle and at the other end by said mass and having means providing a recess which is adapted to enclose and closely confine said mass and extinguish the flame thereof, the 20 length of said rod between said handle and said mass being much greater than that of said snuffing device.

2. An igniting device for oil burners comprising a long slender rod having a handle at the upper 25 end and a porous mass at the lower end, a snuffing device for the flame of said porous mass, said device being freely slidable on said rod and retained against detachment therefrom at one end by said handle and at the other end by said mass 30 and having means providing a recess which is adapted to enclose and closely confine said mass and extinguish the flame thereof, and said device having handle-means adapted to be disposed adjacent said handle of said rod when said 35 snuffing device is at the upper end of said rod so that said handle-means and said handle can be concurrently grasped to hold said snuffing device at the upper end of said rod when said igniting device is in use, the length of said rod between 40 said handle and said mass being much greater than that of said snuffing device.

3. An igniting device for oil burners comprising a rod having a handle at its upper end and an ignition element including a porous mass at 45 its lower end, and a snuffing device slidable on said rod comprising a circular plate which is freely slidable on said rod and is retained thereon between said handle and element, said plate having an annular depending rim and a depending 50 tubular member located within said rim having a recess adapted to receive and closely confine said element, the length of said rod between said handle and said mass being much greater than that of said snuffing device.

IVAN V. ABADJIEFF.
